(57) **CLAIM**

The ornamental design for a fishing jig, as shown and described.

DESCRIPTION

FIG. 1 is a right side elevational view showing my new design for a fishing jig;

FIG. 2 is a left side elevational view;

FIG. 3 is a top plan view;

FIG. 4 is a bottom plan view;

FIG. 5 is a front elevational view; and,

FIG. 6 is a rear elevational view.

The broken lines shown in FIGS. 1 and 2 represent environment and are included for the purpose of illustrating only and form no part of the claimed design.
